JAR

Baker L. Shannon, Houston, Tex.

Application July 13, 1936, Serial No. 90,833

4 Claims. (Cl. 255—27)

This invention relates to a jar.

An object of the invention is to provide a jar adapted to be connected into an operating string of pipe which, in turn, may be connected to the pipe or other object stuck in a well bore and whereby the stuck pipe may be vibrated or jarred and thus more readily released and removed from the well bore.

As is well known pipe often becomes stuck in a well bore and in such a case it is common practice to lower a grapple attached to an operating string into the well and to engage the stuck pipe to pull the same from the well. Often times the pipe is so tightly stuck that it can not be pulled from the well and in such case it is advantageous to connect a jar into the operating string and by operation of which the stuck pipe may be vibrated or jarred and thereby released.

The invention herein described comprises a novel type of jar for the purpose herein indicated.

It is another object of the invention to provide a jar that may be operated irrespective of the tension on the operating string.

It is a further object of the invention to provide a jar of the character described that can be controlled by the application of fluid under pressure exerted through the operating string by a pump at the ground surface.

It is still a further object of the invention to provide a jar of the character described that is of such construction that it may be readily connected into the operating string and lowered into the well and that may be operated by the application of fluid under pressure.

With the above and other objects in view the invention has particular relation to certain novel features of construction, operation and arrangement of parts, an example of which is given in this specification and illustrated in the accompanying drawing wherein:

Figure 1 shows a vertical sectional view of the jar, shown in released position with the parts in the position they will occupy upon an impact stroke of the jar.

Figure 2 shows a vertical sectional view of the jar with the impact member locked in inactive position.

Figure 3 shows a fragmentary vertical sectional view, showing the parts in position to be released to effect an impact stroke.

Figure 4 shows a cross sectional view taken on the line 4—4 of Figure 2, and

Figure 5 shows a diagrammatic view illustrating

ing the jar connected into the operating string with the grapple connected to the stuck pipe.

Referring now more particularly to the drawing wherein like numerals of reference designate the same parts in each of the figures, the numeral 1 designates a tubular housing to the lower end of which a reducing nipple 2 is attached, the housing and nipple being separated by a transverse partition 3.

The lower end of the nipple terminates in an outwardly threaded pin 4 which may be screwed into a length of tubing 5 to which any conventional type of grapple 6 may be attached. This grapple is of well known construction and is of the releasable type and may be readily engaged with or relieved from the stuck pipe 7.

Connected to the partition 3 and extending through it there is a lower cylinder 8 which is provided with the upper ports 9 spaced apart above the partition and the lower ports 10 immediately beneath said partition. The upper end of the cylinder 8 is closed except for the central bearing 11 through which the stem 12 works. The upper end 13 of the stem is tapered and attached to the lower end of the stem there is a plunger 14. A plug 15 closes the lower end of the cylinder and between said plug and the plunger 14 there is a coil spring 16 which normally holds the plunger elevated as shown in Figure 2. The lower end of the cylinder is provided with a vent 17.

Pivoted on and upstanding from the upper end of the cylinder are the oppositely arranged complementary links 18 whose upper ends are hemispherical in shape forming the complementary outwardly curved bosses 19, 19. The numeral 20 designates an operating string of pipe whose lower end is connected to the upper end of the tubular shank 21. Throughout the major portion of its length this shank is polygonal in cross section, said polygonal portion working through a correspondingly shaped bearing 22 in the sectional gland 23 which is screwed into and forms a closure for the upper end of the housing 1. This gland is pinned in place by the pins 24 and contains the packing 25 which forms a close fit between the gland and the shank 21. The lower end of the gland has the radial grooves 26 as more clearly shown in Figures 1 and 2.

Within and spaced from the housing 1 and attached to the lower end of the shank 21 there is the upper cylinder 27 whose upper end is closed and whose lower end is open. This cylinder has an annular impact face 28 located at its upper end. The operating string 20 and shank 21 are

The drawing and description disclose what are now considered to be preferred forms of the invention by way of illustration only while the broad principle of the invention will be defined by the appended claims.

5

What I claim is:

- 5 Fitted snugly within the cylinder 27 there is a piston 30 which is supported on a coil spring 31 and the lower end of this spring surrounds the lower cylinder 8 and is supported on the partition 3. This spring 31 is not indispensable.
- 10 The upper end of the piston 30 is formed with an annular impact face 32 arranged opposite the impact face 23. The lower end of the piston 30 is formed with a socket 33 positioned to receive and interlock with the bosses 19, 19 when said piston is in its lower position as shown in Figure 2. In operation the jar is assembled with the operating string 20 and with the grapple connected thereto and as so assembled is let down into the well to bring the grapple into engagement with the stuck pipe 7. While being so lowered the pump will be stopped and the plunger 14 not being subjected to the pump pressure will be elevated by the spring 16. At this time the stem 12 will be in its elevated position and the links 18 will be in their outer position as shown in Figure 2 but the piston 30 will be in its upper position as shown in Figure 1. The pump may be now started and liquid under pressure will be forced down through the operating string and the shank 21 and out through the ducts 29 in the grooves 26 and will pass on downwardly through the upper ports 9 and force the plunger 14 downwardly to clear the lower ports 16, the liquid beneath the plunger being relieved through the vent 17 and the spring 16 being placed under compression. The tapering portion 13 of the stem 12 will thereby be withdrawn from between the links 18 and they will fall inwardly into the position shown in Figure 1. The operating string 40 20 may now be lowered forcing the upper cylinder 27 downwardly until the bosses 19 are received by the socket 33 and the pump pressure again relieved, whereupon the spring 16 will elevate the plunger rod 12, forcing the links 18 apart as shown in Figure 2 and thus locking the piston 30 in its lower position as shown in Figure 3. The operating string 20 may now be pulled upwardly withdrawing the cylinder 27 into its upper position as shown in Figure 3 thus creating a vacuum in said upper cylinder. The pump may then be again started forcing the plunger 14 downwardly, as before, and withdrawing the upper end of the stem 12 from between the links 18, permitting said links to move inwardly and releasing the piston 30. When the piston 30 is moved downwardly the spring 31 is placed under compression as shown in Figures 2 and 3 and upon release of the piston 30 the vacuum above it, combined with the pressure of the spring 31 beneath it, will cause said piston 30 to move upwardly at high speed, causing the impact face 32 to strike the opposing face 28 violently. At this time the operating string 20 may be under any desired tension so as to exert a constant upward pull on the stuck pipe and the jar incident to the impact will, in most cases, be effective to release or assist in releasing the stuck pipe. The operation may be repeated as often as necessary in order to completely release the stuck pipe 7.
- 15 A jar comprising a housing, a grapple attached to the housing, a cylinder in the housing having an impact abutment, a piston in the cylinder having an impact face opposite said abutment, means on the housing and piston adapted to interlock, said cylinder and piston being simultaneously movable into one position to cause the interengagement of said interlocking means to hold the piston stationary in the housing, said cylinder being movable independent of the piston to another position to cause a vacuum to be created in said cylinder and means arranged to be controlled by pressure fluid and adapted to release said interlocking means whereby to release the piston to permit said impact face to strike against said abutment.
- 20 A jar comprising a housing, means for connecting the housing to a grapple, an operating string associated with the housing, a lower cylinder in the housing, a plunger yieldingly mounted in said lower cylinder, an upper cylinder in the housing connected to the operating string, a piston in the upper housing, means on the lower cylinder engageable with the piston, means on the plunger normally operative to maintain such engagement, said piston and upper cylinder having opposing impact faces, said jar having a passage-way therethrough for fluid pressure and said plunger being operable by said pressure to release 30 said engaging means.
- 25 A jar comprising a housing, grappling means connected to the housing, a cylinder in the housing, an operating string operatively connected with the housing and to which the cylinder is attached, a piston in the cylinder, said cylinder and piston having opposing impact faces, a locking device engageable with the piston, said cylinder and piston being simultaneously movable to position to engage the piston with the locking device and the cylinder being movable to another position to create a vacuum within the cylinder and means arranged to be operated by fluid under pressure, exerted through the operating string, to release the locking device from the piston.
- 30 35 A jar comprising a housing, grappling means connected to the housing, a cylinder in the housing, an operating string operatively connected with the housing and to which the cylinder is attached, a piston in the cylinder, said cylinder and piston having opposing impact faces, a locking device engageable with the piston, said cylinder and piston being simultaneously movable to position to engage the piston with the locking device and the cylinder being movable to another position to create a vacuum within the cylinder and means arranged to be operated by fluid under pressure, exerted through the operating string, to release the locking device from the piston.
- 40 45 A jar comprising a housing, grappling means connected to the housing, a cylinder in the housing, an operating string operatively connected with the housing and to which the cylinder is attached, a piston in the cylinder, said cylinder and piston having opposing impact faces, a locking device engageable with the piston, said cylinder and piston being simultaneously movable to position to engage the piston with the locking device and the cylinder being movable to another position to create a vacuum within the cylinder and means arranged to be operated by fluid under pressure, exerted through the operating string, to release the locking device from the piston.
- 50 55 A jar comprising a housing, grappling means connected to the housing, a cylinder in the housing, an operating string operatively connected with the housing and to which the cylinder is attached, a piston in the cylinder, said cylinder and piston having opposing impact faces, a locking device engageable with the piston, said cylinder and piston being simultaneously movable to position to engage the piston with the locking device and the cylinder being movable to another position to create a vacuum within the cylinder and means arranged to be operated by fluid under pressure, exerted through the operating string, to release the locking device from the piston.
- 60 65 A jar comprising a housing, grappling means connected to the housing, a cylinder in the housing, an operating string operatively connected with the housing and to which the cylinder is attached, a piston in the cylinder, said cylinder and piston having opposing impact faces, a locking device engageable with the piston, said cylinder and piston being simultaneously movable to position to engage the piston with the locking device and the cylinder being movable to another position to create a vacuum within the cylinder and means arranged to be operated by fluid under pressure, exerted through the operating string, to release the locking device from the piston, and a yieldable member operative to actuate the piston when released and effective to drive the piston into contact with the impact face of said cylinder.
